CLAIM

The ornamental design for an end cap for information tube, as shown and described.

DESCRIPTION

FIG. 1 is a perspective view of an end cap for information tube showing my new design;

FIG. 2 is a side view of the end cap for information tube;

FIG. 3 is an opposite side view of the end cap for information tube;

FIG. 4 is a top view of the end cap for information tube;

FIG. 5 is a bottom view of the end cap for information tube;

FIG. 6 is a front view of the end cap for information tube;

FIG. 7 is a rear view of the end cap for information tube; and,

FIG. 8 is a perspective view of the end cap attached to an information tube and opposing end cap shown in broken lines.

The broken lines shown in FIG. 8 form no part of the claimed design.
